EDWIN JAY KOONTZ, OF WADSWORTH, OHIO.

PROCESS FOR COVERING THIN ARTICLES WITH PYROXYLIN COMPOUNDS.

1,148,908.

Specification of Letters Patent.

Patented Aug. 3, 1915.

Application filed January 20, 1915. Serial No. 3,313.

To all whom it may concern:

Be it known that I, EDWIN JAY KOONTZ, a citizen of the United States, residing at Wadsworth, in the county of Medina and State of Ohio, have invented new and useful Improvements in Processes for Covering Thin Articles with Pyroxylin Compounds, of which the following is a specification.

This invention relates to improvements in processes for covering articles with a pyroxylin compound, and the object thereof is to provide a process by which relatively thin articles of wood can be covered with a pyroxylin compound without warping and distorting the article. Briefly, this invention has no relation to the covering of wood articles of such thickness as to be stable against warping or distorting when covered with a pyroxylin compound.

This process is designed solely for the covering of thin pieces of wood, such for instance as hand mirrors, where a recess is provided in one of the faces thereof to receive the mirror, which renders the wood so thin as to be insufficient to resist warping and distortion due to the pulling and contracting in the hardening, drying and setting of the pyroxylin compound. The manufacture of thin articles covered with pyroxylin has heretofore been attended with great expense, due to the necessity of providing separate molds for molding the separate sizes and shapes made. Experience has shown that when the softened pyroxylin compound is applied to the wood a "sweating", so called, is produced, which moisture entering the wood causes it to warp as the pyroxylin and wood dry.

The primary object therefore of this invention is to provide a process by which thin bodies of wood can be covered with a pyroxylin compound without warping or distorting the wood and without the necessity of using molds.

The drawing presented is a fragmentary view of a hand mirror which will serve to illustrate the application of the process which forms the basis of this invention, but it is to be understood that while the illustration shows a portion of a hand mirror, which has been selected simply as a convenient article for illustration, any other well known article of wood which is relatively thin might be equally as well employed.

It is to be understood that the invention applies to the covering of any article of

wood which is too thin to successfully resist distortion or warping following the covering thereof by a coat of pyroxylin compound.

The first step in the process, and which while exceedingly useful, is not absolutely essential, is to coat the article, hereinafter denominated as a mirror frame 1, with a layer of flat white paint 2. This layer of paint is used to cover the grain of the wood as the covering layer of the pyroxylin compound is usually thin; this makes the covering of the article white and opaque to prevent the wood itself showing through the semi-transparent pyroxylin covering. The layer of paint is allowed to dry after which the painted article is covered with a thick layer 3 of cement containing amyl-acetate, pyroxylin-scrap and gum camphor, the proportions of which will vary somewhat with respect to different articles to be covered, and also will vary for other purposes not deemed necessary to amplify here. This layer of cement is allowed to thoroughly dry and the wood article is then ready to receive the covering of pyroxylin sheeting. The pyroxylin sheeting is first softened in the usual manner and the face of the sheet which is to be applied to the article is covered with a coating of the amyl-acetate cement, before mentioned, and also the article itself is likewise covered with the same cement. The face of the layer of pyroxylin sheeting which has been covered with cement is then laid on the article and pressed firmly into shape, all bubbles and irregularities smoothed out and the composite article permitted to dry, after which the roughness due to edge joints, etc., are dressed down and the article is ready for use.

From an extended experience in connection with the application of this process, it is found that the initial coating of the wood article by the amyl-acetate cement and then permitting the same to dry, effectually prevents the moisture from the softened pyroxylin sheeting and the cement used to cause the pyroxylin sheeting to adhere to the wood, from penetrating the latter, thereby preventing said moisture from entering the wood and no warping or distorting of the article takes place.

The necessity for the initial coat of flat white paint does not arise where the pyroxylin sheeting is opaque and which prevents

2
the wood showing through the pyroxylin sheeting and it is only used to give a finished appearance to the article. The article may be covered equally well and equally advantageously and the same results may be obtained if the article is first covered with a solution of the amyl-acetate cement.

I claim:

1. That improvement in methods for covering relatively thin and unsupported wooden articles with a pyroxylin compound which consists in coating the article with a cement containing amyl-acetate, pyroxylin-scrap and gum-camphor, drying the same, re-coating the coated article with a similar solution, coating a previously softened sheet of pyroxylin compound with the same solution and then applying the coated face of the pyroxylin compound to the coated face of the article and shaping the same, then drying the composite article.

2. That improvement in methods for coating relatively thin and unsupported wooden articles with a pyroxylin compound which consists in covering the article with a paint, 25 drying the paint, covering the painted article with a cement comprising a solution of amyl-acetate, pyroxylin-scrap and gum-camphor, drying said cement, softening a sheet of pyroxylin compound, coating one 30 face thereof with the cement solution, re-coating the coated article with said cement solution, applying the coated face of the pyroxylin compound to the article.

In testimony whereof I have hereunto set 35 my hand in presence of two subscribing witnesses.

EDWIN JAY KOONTZ.
